UNITED STATES PATENT OFFICE.

ALBERT R. CORN, OF DENVER, COLORADO.

BRAKE-BLOCK HOLDER.

1,048,043.

Specification of Letters Patent. Patented Dec. 24, 1912.

Application filed June 24, 1912. Serial No. 705,475.

To all whom it may concern:

Be it known that I, ALBERT R. CORN, a citizen of the United States, residing at Denver, in the county of Denver and State 5 of Colorado, have invented certain new and useful Improvements in Brake-Block Holders; and I do hereby declare the following to be a full, clear, and exact description of the invention, such as will enable others skilled in the art to which it appertains to make and use the same.

This invention relates to devices for securing the brake-block to the brake-beam or brake-lever of a vehicle; and it consists of 15 pivoted bell-crank levers which grip the brake-block and which are clamped upon it by improved operating devices as herein-after fully described and claimed.

In the drawings, Figure 1 is a plan view 20 of an end portion of a brake-beam or brake-lever provided with fastening devices for the brake-block according to this invention. Fig. 2 is an end view of the same, partly in section.

25 The brake-beam or brake-lever 2 is of any approved kind such as used on vehicles. Four similar bell-crank levers 3 are pivoted to the beam and are arranged right and left and in pairs. These levers have pivot pins 30 or bolts 4 which have heads 5 at one end, and shoulders 6 and screwthreaded portions 7 at the other end. Two of the bell-crank levers have screwthreaded hubs 8 which are screwed on the parts 7, against the shoulders 6, so that nuts are dispensed with. These bell-crank levers have jaws 10 at one 35 end which engage with the brake-block 11, and the jaws are preferably serrated so that the block cannot slip.

40 Clamping bolts 14 are provided having sockets 15 which engage with the other end portions 16, and the end portions have lateral projections 17 which retain the sockets in position.

45 A plate 18 is arranged at the back of the beam 2, and this plate has elongated holes or slots 19 for the clamping bolts, so that it can be used on beams of different thickness.

Washers 20 are slid upon the pivot bolts, and are arranged between the brake-beam 50 and the hubs of the bell-crank levers so as to adjust them to different brake beams. When the fastening devices are constructed in this manner, they are greatly simplified, and cost very little to manufacture, and at 55 the same time are very efficient in action.

What I claim is:

1. The combination, with a brake-beam, and a brake-block; of bell-crank levers pivoted to the beam and arranged in pairs at 60 opposite sides thereof, each pair of bell-crank levers being provided at one end with jaws for engaging with the brake-block and having their other end portions arranged substantially in alinement with each other, 65 a clamping plate engaging with the brake-beam, and two clamping bolts having nuts at one end and rectangular sockets at the other end which engage pivotally with the alined end portions of the pairs of bell- 70 crank levers.

2. The combination, with a brake-beam, and a brake-block; of bell-crank levers pivoted to the beam and arranged in pairs at 75 opposite sides thereof, each pair of bell-crank levers being provided at one end with jaws for engaging with the brake-block and having their other end portions arranged substantially in alinement with each other, each alined end portion having also a laterally projecting stop or guide, a clamping plate engaging with the brake-beam, and two clamping bolts having nuts at one end 80 and rectangular sockets at the other end which engage pivotally with the alined end 85 portions of the pairs of bell-crank levers and work between the said laterally projecting stops or guides.

In testimony whereof I have affixed my signature in the presence of two witnesses. 90

ALBERT R. CORN.
